UNITED STATES PATENT OFFICE.

HOMER C. THRIFT, OF GOOSE CREEK, TEXAS.

PIPE-PULLING DEVICE.

1,312,009.

Specification of Letters Patent.

Patented Aug. 5, 1919.

Application filed December 18, 1918. Serial No. 286,978.

To all whom it may concern:

Be it known that I, HOMER C. THRIFT, a citizen of the United States, residing at Goose Creek, in the county of Harris and 5 State of Texas, have invented certain new and useful Improvements in Pipe-Pulling Devices, of which the following is a specification.

This invention relates to new and useful 10 improvements in a pipe pulling device.

The object of the invention is to provide a device of the character described, which is specially designed for pulling pipe from wells.

15 Another object of the invention resides in the provision of a device of the character described, which will automatically engage with the pipe to elevate the same, and which will automatically grip and hold the pipe 20 at any point of elevation.

A further feature of the invention resides in the provision of a device of the character described, which is readily accessible to those working on the derrick floor, and which may 25 be conveniently manipulated.

A still further feature of the invention resides in the provision of a pipe pulling device, which may be cheaply and easily constructed and easily operated.

30 With the above and other objects in view, the invention has particular relation to certain novel features of construction, use and arrangement of parts, an example of which is given in this specification and illustrated 35 in the accompanying drawings, wherein:

Figure 1, is a fragmentary front elevation of the device, shown partially in section,

Fig. 2, is a fragmentary, transverse, sectional view, taken on the line 2—2 of Fig. 1,

40 Fig. 3, is a fragmentary front elevation.

Fig. 4, is a side view of the pump and connecting parts, and

Fig. 5, is a sectional view of a preferred form of jack employed.

45 Referring now more particularly to the drawings, wherein like numerals of reference designate similar parts in each of the figures, the numeral 1, refers to the base, which has a central opening 2, extending 50 vertically therethrough, and which tapers downwardly, and provided to receive the wedge-shaped slips 3, arcuate in form, to conform to the shape of the opening 2. The inner faces of these slips are serrated, forming the teeth 4, adapted to engage with the pipe 5, to be elevated. The base 1, is ex-

tended each way and rests upon the arches, 6, 6, which rest upon the respective side beams 7, 7, forming supports for the base 1, and these extended ends and the arches have 60 the aligned vertical openings 8, 8, through which the hydraulic jacks, hereinafter described, extend. These jacks include the cylinders 9, 9, in which the plungers 10, 10, operate. The upper ends of the cylinders 65 are formed with annular flanges 11, 11, which engage with the upper side of the base 1, to hold said cylinders suspended from said base. Resting upon the upper ends of the plungers 10, is the head block 12, 70 having the central opening 13, extending vertically therethrough, and tapering downwardly, to receive the wedge-shaped slips 14, which are formed arcuate in cross section to conform to the contour of the opening 13, 75 said slips 14 being similar to the slips 3, and their inner faces being serrated to form engaging teeth 15.

A pump 16 is provided which may be of any desired form, having one or more cylinders depending upon the amount of fluid pressure required. Above the pump is a container 17 provided to contain the motive fluid. The pump operates to withdraw the fluid from the container through the pipe 80 18, which is controlled by the check valve 19, and to force the same out through the pipe 20, through the two-way valve 21, and on through the line 22. This line is divided into 23, 23, which enter the cylinders 9, 9, 85 90 at the bottom.

The pipe 5, to be withdrawn, extends up through the central openings 2 and 13. When pressure is applied to the hydraulic jacks, the plungers 10, 10, are forced upwardly, carrying the head block 12 with them. During this upward movement, the slips 14 engage with and elevate the pipe, the slips 3, releasing the pipe, and permitting it to move upwardly. Meanwhile the 100 cylinders 9 are held in fixed position by means of the flanges 11, which rest upon the base 1. During this operation, the two-way valve 21 is manipulated to permit the passage of fluid from the pipe 20 to the line 22. When the pipe 5 has been elevated, as far as the jacks will carry it, the pump is stopped, and the two-way valve is manipulated to close the pipe 20, and to open the line 22, into communication with the 105 pipe 24. Thereupon the weight of the head block 12 causes the plungers to descend, the 110

slips 14 automatically releasing the pipe and the slips 3 engaging the pipe to hold the same elevated. The fluid is thereby forced out of the cylinders 10 through the branch 5 pipes 23, the line 22, and the pipe 24 back into the container 17. The two-way valve 21 is again manipulated to open the pipe 20 and the pump again started, and another pull thereby exerted on the pipe 5, thereby 10 again elevating it. Thus the pipe 5 is gradually pulled from the hole by successive pulls exerted through the hydraulic jacks, and at all times, held against descending by means of the slips 3, while the head block 15 12 descends to engage with the pipe, preparatory to another pull.

It is to be observed that the cylinders 9 are suspended from and thus located beneath the base 1, so that when the head 20 block 12 is fully elevated, it will not be too high to be readily accessible to the operators.

It has been found that when the cylinders are mounted above the base, the jacks, when fully elevated, will carry the head 25 block 12, and the slips 14 too high for convenient handling.

In Fig. 5, I have shown the preferred form of jack, which may be employed wherein the numeral 9' refers to the cylinder 30 whose upper end is formed with the annular flange 11', which engages with the base 1 to hold the cylinder suspended. In this form of jack, the plunger consists of an outer cylinder 25, 35 and an inner plunger rod 26, the latter telescoping with the former. When a comparatively light load is to be elevated, a collar 27, having an inwardly extending flange 28 is screwed into an internally 40 threaded recess, in the upper end of the cylinder 9', the flange 28 engaging against the upper end of the cylinder 25, and securing said cylinder against elevation. The load is then lifted by means of the plunger 45 rod 26, requiring a less amount of fluid and consequently, less work on the part of the pump. When a heavy load is to be

lifted, the collar 27 is unscrewed and removed, and the cylinder 25 and rod 26 then move upwardly together, thus utilizing the 50 full force of the jack.

What I claim is:

1. A pipe puller consisting of a stationary member, a vertically movable member, means carried by the stationary member 55 to engage and hold the pipe elevated, means carried by the movable member and provided to engage the pipe to elevate it, and jacks sustained by the stationary member and operating against the movable member 60 to elevate the latter, each jack including a fluid pressure cylinder, a plunger operating therein, said plunger including an outer cylinder and a plunger rod telescoping said cylinder, and means to engage said last mentioned cylinder to hold the same against elevation relative to the said fluid pressure cylinder. 65

2. A device for pulling pipe from a well, comprising an oblong base, having a central 70 opening, arches which support the respective ends of said base, and which rest upon a suitable foundation, hydraulic jacks fitted through the ends of said base and through said arches, the upper end of each jack 75 having an annular flange, which engages the base and holds the jacks suspended therefrom, a head block having a central opening mounted upon said jacks, to be operated thereby, said central openings of said base 80 and block admitting the pipe to be pulled, means within said respective openings fitted around said pipe, said means in the opening of the base engaging the pipe to hold it elevated, and the means within the opening 85 of the head block engaging the pipe to elevate it when the head block is elevated.

In testimony whereof I have signed my name to this specification in the presence of two subscribing witnesses.

HOMER C. THRIFT.
